UNITED STATES PATENT OFFICE.

WILLIAM F. LAUTENSCHLAGER, OF CINCINNATI, OHIO, ASSIGNOR TO LORENZ MUTHER,
OF NEWTON, MASSACHUSETTS.

FOLDING-MACHINE.

1,294,919.

Specification of Letters Patent. Patented Feb. 18, 1911.

Application filed June 21, 1911. Serial No. 634,485.

To all whom it may concern:

Be it known that I, WILLIAM F. LAUTENSCHLAGER, a citizen of the United States, residing at Cincinnati, in the county of Hamilton and State of Ohio, have invented certain new and useful Improvements in Folding-Machines, of which the following is a specification.

My invention relates to folding machines particularly applicable for folding the edges of material employed in the manufacture of footwear and other articles in which material of a similar nature may be used, and is arranged, for instance, to fold the cemented or uncemented edges of vamps, quarters, foxings, back-straps, linings, and other parts upon which my improved device may be employed.

The objects of my invention are to provide new and improved means whereby the edge of a piece of material is folded; further to provide new and improved means whereby the edge of the leather operated on is provided with incisions of less length at the flesh side than at the grain side thereof; further to provide a new and improved feeding movement for the feeding foot; further to provide new and improved operative relations between the parts mentioned; further to so arrange the machine that either the cutting or folding means may be rendered inactive; further to provide new and improved means for guiding a piece of material in being fed through the machine whereby especially the folding may take place accurately on arcs of short radii; further to provide new and improved means for controlling the lengths of the steps of feed; further to provide means whereby the lengths of steps of feed may be changed during operation; and, further to provide new and improved means whereby the feeding-foot and presser-foot movements are correlated. It is the object of my invention further to provide means adapted for folding the edges of vamps, comprising an arm projecting outwardly from the frame of the machine over which arm the vamp may be arranged to move in the folding operation, said arm supporting feeding, folding, fold pressing and snipping instrumentalities and operating connections for the said feeding, fold pressing and snipping instrumentalities, the operating connections having connection with the driving means located in the frame of the

machine; to provide new and improved driving means for the feeding-foot whereby great speed of feed may be obtained. The invention will be further readily understood from the following description and claims, and from the drawings, in which latter:

Figure 1 is a front elevation of my improved device partly broken away for better illustration of parts.

Fig. 2 is a rear elevation of the same partly broken away for better illustration of parts.

Fig. 3 is a front-end elevation of my improved device.

Fig. 4 is a rear-end elevation of the same.

Fig. 5 is a plan view of my improved device partly broken away.

Fig. 6 is an end elevation of the eccentric and link mechanism.

Fig. 7 is a detail showing the adjustment for the knife-block in vertical section on the line 7—7 of Fig. 10.

Fig. 8 is a detail in vertical section on the irregular line 8—8 of Fig. 1.

Fig. 9 is a horizontal section on the line 9—9 of Fig. 8.

Fig. 10 is a plan view of the fold-presser and knife-lever connections with the exposure-plate removed.

Fig. 11 is an enlarged front elevation illustrating the relations of the feeding-foot, presser-foot, hold-down, knife, folder and fold-presser.

Fig. 12 is a perspective view of the material operated on showing the operative effects thereon of the machine, and

Fig. 13 is a cross-section of the folded material.

21 represents the main frame, which is shown hinged, as by hinges 22, to a base 23, to which it is suitably secured, as by a clamp 24. The base forms part of the main frame and is arranged to rest upon or be secured to an ordinary work bench or table in ordinary manner. The base may comprise a trough 25 received under the operative parts of the mechanism and acting as a protecting-plate as well as a drip-trough for the oil received from the mechanism. The main frame may be swung on the hinges for exposure of the operating parts under the main table 26. Aprons 27 may depend from the table to lines adjacent to the trough, the ends of which may be connected by a closing plate 28 removably held in place by 105

screws 29. The table 26 with the aprons and protecting plate extend laterally as an arm projecting outwardly from the vertical or upright wall of the column portion of the 5 main frame of the machine. It will be observed that this arm is comparatively small in cross-section.

31 is a drive-shaft operated in suitable manner, as by a pulley 32. The drive-shaft 10 is journaled in suitable bearings 33 of the main frame and it, together with the operating parts of the mechanism, preferably move with said main frame when the same is tilted on the base.

15 34 and 35 are rock-shafts journaled respectively in bearings 36, 37 of a goose-neck bracket 38 over-hanging the table. The rock-shaft 34 is arranged to oscillate the feeding-foot, while the rock-shaft 35 is arranged to raise and lower the presser-foot, and to raise and lower the feeding-foot during the oscillations of said feeding-foot. These longitudinal reciprocating movements of the feeding-foot take place preferably adjacent to the limits of oscillating movement thereof, during the retracting movements of the feeding-foot, whereby extremely rapid operation of the feeding-foot is obtained, for the reason that one of said motions qualifies the other in manner to qualify its direction of movement without acting counter thereto.

39 is a feeding-foot housing secured to the rock-shaft 34 as by a clamp-bearing 40. It 35 has in it a bearing 41 in which the stem 42 of the feeding-foot is arranged to be moved longitudinally, a feeding-foot 43 being on the stem. The stem is normally urged toward the table by a spring 44 between the 40 feeding-foot housing and the stem, shown received over a screw 45 on said housing and a screw 46 on a clamp 47 on the stem, the clamp having a pin 48 extending therefrom, and being adjustable on the stem.

45 There is a washer 49 between the clamp and the bearing end which acts as a cushion to receive the thrust of downward movement of the stem. This washer is preferably a fiber-washer of electro-insulating fiber, being 50 a hard substance which acts as a sound-deadening cushion.

51 is a presser-foot which acts adjacent to the feeding-foot, the feeding-foot preferably acting between the presser-foot and the 55 knife and folder hereinafter mentioned. The presser-foot and feeding-foot preferably operate opposite the periphery of a roller 52, which is preferably a raw-hide roller made of a plurality of raw-hide washers 60 secured together as by gluing, received about a central thimble 53 journaled on a screw-stud 54. The roller serves to support the material which is pressed thereagainst by the presser-foot and feeding-foot. The 65 material of which the roller is composed and

its cylindrical-contact face serve to prevent the adhesion of the material being operated on and is especially advantageous when operating on such materials as patent leathers which have an especial tendency to adhere to metal surfaces.

The presser-foot is on a presser-foot lever 56. The presser-foot is normally pressed toward the table by a spring 57 shown located between a socket-bolt 58 and the lever, the socket-bolt being adjustable in a threaded bearing 59 and held in place by a lock-nut 60. For raising the presser-foot the rock-shaft 35 is provided with a rocker-part 61 having a contact-lug 62 thereon arranged to act against a spring 63 for resiliently raising the presser-foot. The rocker-part 61 is shown as having a clamp-bearing 64 about the rock-shaft 35 by means of which it may be adjustably positioned about said rock-shaft. The spring 63 is a coiled spring of comparatively great resistance and having slight extent of compression, and the contact-lug 62 and the presser-foot lever acts as a cushion between for receiving the initial impact of said contact-lug, and acts as a rigid stem when said slight extent of compression is taken up. It is received in a socket-bolt 65 adjustable in a threaded-bearing 66 of the presser-foot lever and held in place by a jam-nut 67.

71 is a raiser-link for the feeding-foot stem. It is articulated with the arm 72 of the rocker-part 61 at 73 and has a pocket 74 for receiving the pin 48. The movement of 100 the rocker-part 61 is idle with relation to the feeding-foot for part of its range, during which idle relation the feeding-foot is rocked by the rock-shaft 34 in its forward or feeding movement. During this movement the 105 feeding-foot is moved in an arc described from the oscillating axis of the rock-shaft 34, the presser-foot during this feeding movement being in raised position. During the latter portion of this feeding movement, 110 the raiser-link moves idle upwardly with relation to the feeding-foot or device accomplished by the space 75 between the bottom of its pocket 74 and the pin 48, during which movement also the presser-foot descends 115 upon the material, the contact-lug 62 receding sufficiently preferably for being spaced from the end-contact member or spring 63 when the feeding-foot is in raised relation. At about the point that the feeding-foot under which term I include any other feeding-device, has return oscillation imparted to it, the raiser-link 71 contacts the pin 48 for complementing the oscillating movement of the feeding-foot or device with a raising 120 movement thereof. This raising movement and the corresponding descending movement take place during the return oscillation of the feeding-foot or device.

The movement of the feeding-foot is ac- 130

complished therefore by an oscillating movement thereof complemented by a longitudinal reciprocating movement taking place during the oscillation of the same, for qualifying that oscillating movement by supplemental movements directed in lines substantially parallel with the longitudinal projection of the feeding-foot stem, irrespective of the oscillatory position of said stem. It will be noted from Figs. 3 and 6 that the pivotal axis of the raiser-link 71 is substantially coincident with the rocking axis of the rock-shaft 34 and substantially intersects the longitudinal axis of the feeding-foot stem.

81 is a folder shown as comprising a bar 82 having a folding-throat 83 and preferably slidable toward and from the presser-foot in a guide-way 84 of a guide-block 85, removably secured to an exposure-plate 86 by a screw 87. The exposure plate forms a part of the table 26. It is held in operative position by a pin 88 arranged to enter an aperture 89 on the guide-block when in operative position and an aperture 90 on said 25 guide-block when in inactive relation. This pin is preferably on a spring-plate 91 which has adjustable connection with the bar 82 by being provided with a slot 92 through which a fastening screw 93 is arranged to be received into the bar 82. The adjustment of the spring-plate 91 with relation to the bar adjusts the relation of the folding-throat 83 to the feeding-foot for accommodating, for instance, leathers of different thicknesses, or 35 providing more or less abrupt folds.

The feeding-foot has a nose 96 arranged to be received past the forward wall of the folding-throat, that is, the wall nearest the operator, (see Fig. 9), adjacent to the table 40 whereby on proper adjustment of the folder, a crease indicated at 97 is formed in the material shown at 98, thereby aiding in determining the exact line of the fold along which the material is definitely bent by the fold- 45 presser 99.

This fold-presser is on a lever 101 pivoted about a rod 102 secured in bearings 103 in the outer end of the outwardly projecting arm of the frame. Its pivot is in a vertical 50 plane to the side of the folding-jaw of the fold-presser, whereby the jaw is moved toward the material with a motion which is downward and approaching with relation to the material for laying the material over in 55 its proper fold for completing the fold and pressing the folded edge.

The fold pressing member is located in the outer end of the outwardly projecting arm, the pressing jaw thereof projecting upwardly through the material supporting table while the same is mounted and its operating parts are located in the outer end of said arm, connections for operating the same being also located in said outer end of said 60 outwardly projecting arm and connecting

with the operating parts which extend from the column of the frame.

The nearer this pressing of the fold approaches a semblance to hand-pressing such as would be accomplished by the pressure of 70 the finger upon the fold, the more accurate it will be and the less danger will there be of injury to the material. The means I employ operate in this manner for effecting the laying down of the fold with pressure rather than with a blow, and I aid in accomplishing this by operating the fold-presser from a point closely adjacent to its pivot whereby I avoid detrimental inertia of motion of parts and the detrimental results of lost motion of 80 parts.

107 is a presser-housing pivoted on bearings 108 about the rod 102 and having a tail 109 provided with a recess 110 in which the tail 111 of the fold-presser is located, 85 preferably adjustably and resiliently. For providing the adjustment, the tail of the presser is provided with an adjusting screw 112 received against a wall 113 of the recess and held in place by a jam-nut 114. The 90 resilience of the presser is accomplished by a spring 115 acting to force the adjusting screw 112 against the wall 113 and received in a socket 116 on the tail 111 and a socket 117 of an adjusting screw 118 having a 95 threaded bearing 119 in the wall 120 of the recess 110. This adjusting screw is provided with a bore 121. The adjusting screw 112, the spring 115 and the adjusting screw 118 provided with its bore 121 are arranged 100 in axial alinement so that a screw-driver may be received through said bore and spring for adjusting the adjusting screw 112. This arrangement of parts accomplishes the further purpose that the pressure 105 of the spring is exerted in axial line with the contact point of the adjusting screw 112 upon the presser-housing so that the pivotal bearing of the presser-housing and presser-lever may be relieved from the 110 strain of the spring. The operating parts just described are located in the outer end of the outwardly projecting material-supporting arm.

For oscillating the presser-housing I provide it with a lug 126 which has operative connection with the drive-shaft 31 closely adjacent to the pivotal axis of said housing. Thus I provide the lug with a bearing 127 about a bearing-pin 128 which has connection with the drive-shaft by a universal joint connection comprising the links 129, 130 and 131, the links 129 and 130 being connected by a bearing-pin 132, and the links 130 and 131 by a bearing-pin 133, the 125 link 131 having a bearing 134 about a stud 135 eccentrically placed on the drive-shaft. The driving connections thus formed are very compact and are all located within the outer end of the overhanging material-supporting 130

arm. By this means close driven articulations are formed between the drive-shaft and the presser-housing, the pivotal axes of which are in closely adjacent planes in the 5 outer end of said outwardly projecting arm. 141 is a knife-lever which has a bearing 142 about the rod 102 and has drive connection in said outer end of said outwardly projecting arm from the universal joint 10 connecting with the drive-shaft, as by being provided with a lug 143 which has a link 144 articulated therewith at 145, the link having a bearing 146 about the bearing-pin 128, preferably about an eccentric 147 thereon for the purpose to be presently described, 15 said lug, links, bearing-pin and eccentric being located in said outer end of said outwardly projecting arm. The knife-lever has a lateral extension 148 received above 20 the folder-bar 82 and is arranged to have a knife 149 adjustably secured thereto for locating the knife closely adjacent to and in front of said folder-bar. The knife is adjustable, as by being provided with a 25 slot 150 through which a screw 151 is received into the knife-lever. The knife-lever is mounted and has operative connection within said outer end of said outwardly projecting arm, the said knife-lever extending 30 upwardly through the material-supporting table of said outer end, the connecting means for operating said knife-lever being also located within said outwardly projecting arm and connecting with the operating devices mounted in the column of 35 the machine.

The knife has a lateral cutting edge 152 and a bottom cutting edge 153 extending at acute angles with relation to each other for 40 forming preferably an entering point 154 for the knife. The knife-lever is pivoted in a vertical plane to the side of the said cutting edge and it swings about said pivotal axis with a motion which, in the form shown 45 causes the entering point 154 to first enter the material to be cut. The lateral cutting edge 152 is shown as extending upwardly and laterally away from the feeding-line. The movement of the knife causes the cutting 50 edges to move toward the feeding-foot and into the material in a lateral and downward direction for accomplishing the cutting with a shearing cut and causing an incision which is of greater length at the bottom than at the top face of the material.

This bottom face in practice, when leather is used as the material, is the grain side of the leather and the top face is the flesh side of the leather. The flesh side of the leather 60 is the side that imparts strength to the leather, the grain side being the finished side. In my improved device therefore I retain the strength or body of the leather, so that when the folding has taken place the 65 fold will be made in an uncut flesh portion

of the leather, as clearly shown in Figs. 12 and 13. The cutting being further accomplished with a shearing cut, can be done with a clean cut without slivering the material.

In some characters of work and in selective portions of other work the folding may be done without the necessity of slitting the material and for enabling this to be done during operation of the machine, the 70 bearing 146 for the link of the cutter-lever is received about the eccentric 147 which is on the bearing-pin 128. This pin is a rocker-pin and has an arm 157 secured thereto which connects with a link 158 by an articulation 159. 160 is a rock-shaft journaled in bearings 161 of the main frame and has an arm 162 thereon with which the link 158 is articulated at 163. An operating arm 164 is secured to the rock-shaft 160 and has connection with a suitable pull-rod 165 leading, for instance, to a treadle or other suitable device by which the eccentric 147 may be turned for maintaining the knife in raised 80 position. The rock-shaft 160 is normally retracted by a spring 166. For limiting the movements of the rock-shaft, the arm 164 is provided with a recess 167 in which a pin 168 secured in one of the bearings 161 is received, the walls of the recess striking the 85 pin and limiting the extent of rocking of the rock-shaft 160.

171 is a gage for the material having a guiding-face 172 and is secured to the removable exposure-plate 86 by a screw 174 received through a slot 175 in the gage for adjustably positioning the gage with relation to the knife and folder parts. It also preferably has on it, for being adjustable therewith, a hold-down spring 176 secured thereto by a screw 178 and received in a slot 177 in the gage for laterally positioning the same.

The removable exposure-plate is received over the rod 102 and parts mounted thereon 110 and the universal joint connections, so that upon removal of the plate the said parts may be exposed. The plate is removably held in place by a screw 179.

181 is a stationary block with relation to 115 which the knife 149 acts for slitting the material. This block is adjustable toward and from the movable knife by having a clamp-screw 182 received therein through a slot 183 in the main frame.

The presser-foot is pivoted on rock-shaft 191 journaled in a bearing 192 of the main frame. In order to control its approach toward the table or the material-supporting roller mounted therein, I provide said rock-shaft with an arm 193 preferably mounted on a clamp 194 arranged to be clamped about the rock-shaft for positioning the arm axially with relation thereto, there being a cushion-block 195 between the main frame 125 130

- and said arm, shown received in a socket 196 of said arm, said cushion being preferably a block of electro-insulating fiber, and is arranged to relieve the impacts of the presser-foot lever. The arm 193 is preferably so adjusted that when the presser-foot is in down position it will be located slightly raised from the roller, the feeding-foot being preferably correspondingly adjusted so that when the machine runs idle the said feet will be out of contact with said roller, but be located sufficiently close thereto, however, to feed the material which may be placed thereunder.
- 15 In my improved device the material may be fed through the machine and be provided with incisions and be folded and the folds pressed, or if desired the material may be folded without being slit, as by rendering the knife inactive, or the material may be cut without being folded, as by rendering the folder inactive by placing it in inoperative position, in which latter case the fold-presser while going through its motions will have no 20 pressing action on the material for the reason that the latter is unfolded and therefore too thin for the presser to have pressing effect thereon.
- 25 The means provided for operating the feeding-foot and presser-foot enable these parts to be operated with great rapidity and for further aiding in great rapidity of operation of the machine and for permitting adjustment of the lengths of steps of feed during operation I provide the following instrumentalities:
- 30 201 is a rock-shaft journaled in a bearing 202 of the main frame. Its rocking axis is preferably in offset relation to the 35 rocking axis of the rock-shaft 34. It has an arm 203 fast thereon, as by means of a clamp-bearing 204, the arm being articulated at 205 with a link 206 having a bearing 207 thereon about an eccentric 209 on the drive-shaft. Rock-shaft 201 also has an 40 arm 211 fast thereon, as by a clamp-bearing 212. Rock-shaft 34 has an arm 213 fast thereon, as by a clamp-bearing 214. 215 and 216 are a pair of links, one of which is 45 articulated on a pin 217 with the arm 211 and the other of which is articulated by a pin 218 with the arm 213, a pin 219 having connection with the outer ends of said links 215 and 216 for pivotally connecting said 50 outer ends. The links 215, 216, constitute a compression-member and a tension-member at each movement of the links, the link 216 being the compression-member and the link 215 the tension-member in the present 55 exemplification while the feeding-foot is being moved in its feeding movement, the link 216 being the tension-member and the link 215 the compression-member while the feeding-foot is being moved in its retracting movement. Said links are arranged 60 substantially parallel with each other, side by side, with the pivotal axes at the respective ends of said links substantially coincident.
- 65 The pivotal connection 219 is arranged to be placed in axial line with the rock-shaft 201. When so placed the oscillation of the rock-shaft 201 has no effect on the rock-shaft 34 and consequently, there is no feeding movement imparted to the feeding-foot. 70 If however the pin 219 is placed out of axial line with the rock-shaft 201 there will be oscillation imparted to the pin 219 through the arm 211 and link 216, the extent of oscillation depending on the distance 75 of removal of the axis of the pin 219 from the axis of the rock-shaft 201, in other words, upon the angular distance between the arm 211 and the link 216, with consequent rocking of the rock-shaft 34 through 80 the medium of the link 215 and the arm 213, thereby determining the extent of oscillating movement of the feeding-foot and the lengths of steps of the feed imparted thereby. The forward limit of movement of 85 the feeding-foot however remains the same irrespective of adjustment of length of feeding stroke of the feeding-foot, the adjustment affecting the retracting limits of said feeding-foot only. The feeding strokes 90 therefore end in similar relations to the knife, folder and presser irrespective of the lengths of feeding strokes for always placing the material in definite relations to these parts. The lengths of feeding strokes may 95 also be adjusted during operation.
- 95 The relations of the parts shown in the drawings are at an intermediate portion of a stroke of the feeding-foot. (See Figs. 3 and 4.) When the parts are positioned 100 so that the feeding movement is *nil*, then the axes of the rock-shaft 201 and the pin 219 are coincident, and the axes of the pins 217 and 218 are also coincident.
- 105 If it is desired to have a feeding movement, the axis of pin 219 is moved out of coincidence with the axis of the rock-shaft 201, *e. g.*, as shown in Figs. 3 and 4, with the result that, upon operation of the machine, there is a movement imparted to the 110 pin 218 due to the angular relation of the axes 201, 217 and 219. At the beginning of this movement the feeding-foot is at its forward limit of movement.
- 115 The beginning of this movement is coincident with the positioning of the high point of the eccentric 209 in extreme upper position, and the completion of this movement and consequent return of the feeding-foot to initial position is coincident with the return, 120 at the end of its revolution, of said high point of said eccentric to said uppermost position. When said eccentric is in said uppermost position the feeding-foot is, as stated, at its extreme forward limit of move- 125
- 130

ment; that is to say, at its position adjacent to the folder and fold-presser, and this position is the same, irrespective of the angular relations of the axes 201, 217 and 219, the 5 axis of the pin 218 being coincident with the axis of pin 217, when the parts are at such limits of their movements. Consequently, the forward limit of movement of the feeding-foot will always be the same, 10 irrespective of the length of feeding stroke imparted by the angular relations of the parts stated.

For positioning the outer ends of the links 215 and 216 with relation to the rock-shaft 201, the pin 219 has articulation with a link 221 which in turn has articulation at 222 with one arm of a lever 223 having a bearing 224 about the rock-shaft 35. The other arm of the lever has connection with a rod 225 leading to a suitable treadle or other operating device, for swinging the lever 223, a spring 226 normally retracting said lever.

227 and 228 are a pair of stops adjustable 25 lengthwise of a guide 229. These stops may be placed according to the limits of movement desired in the feeding-foot, one of the stops determining the minimum of 30 lengths of feeding movement and the other the maximum of said lengths. Thus the lever may be normally forced against the stop 227 by the spring 226, which may represent the minimum lengths of feeding movement. If 35 it is desired to increase the length of steps the lever may be moved toward the other stop. These lengths are limited by the position of said other stop, the positions of both stops, however, being preferably adjustable.

231 is an arm fast on the rock-shaft 35, 40 as by a clamp-bearing 232, and 233 is a link having articulation with the arm at 234. This link has a bearing 235 about an eccentric 236 on the drive-shaft. By these means the rock-shaft 35 is rocked, thereby 45 accomplishing the reciprocating movements of the feeding-foot 43 and the movements of the presser-foot 51 hereinbefore described in connection with the description of said parts and of the raiser-link 71 for the feeding-foot stem 42.

The high points of the eccentrics 209 and 55 236 are placed at such angular distance apart on the drive-shaft 31 as to cause the proper timing of the movement of the feeding-foot and presser-foot hereinbefore described.

The knife, gage and hold-down spring are closely adjacent to each other, and 60 closely adjacent to the folder, the feeding-foot operating closely adjacent to the curved or folding face of the folder, between said latter face and the presser-foot, which latter is closely adjacent to the feeding-foot. The parts are placed in such manner as to permit 65 the movement of the material in arcs,

having short radii for permitting material to be folded along such arcs and in any other curves that may be desired and also in straight lines. For aiding in the curved movement of the material, the rear of the 70 throat of the fold-presser is recessed as shown at 238.

My improved device is simple and compact in its construction, all of the parts which operate upon the material being 75 placed in closely adjacent relations, and the means for operating said parts are such that excessive jarring is avoided, and the power applications of pivoted parts are closely adjacent to their pivotal points for avoiding 80 the detrimental effects and abnormal jarrings due to inertia of motion and for reducing the inertia. My improved construction permits a large output to be obtained, and 85 very rapid operation of the parts.

Having thus fully described my invention, what I claim as new and desire to secure by Letters Patent is:

1. In a folding machine, an oscillatory feeding-foot housing, a feeding-foot having 90 a stem guided by and reciprocating lengthwise of said housing and means for reciprocating said stem comprising a rocker-arm and a link having a pivotal connection whose axis is substantially coincident with the oscillatory axis of said housing during part 95 of the movement of said connection.

2. In a folding machine, an oscillatory feeding-foot housing, a feeding-foot comprising a stem, guiding means between said feeding-foot housing and stem, and means for reciprocating said feeding-foot stem lengthwise of said guiding means comprising a rocker-arm and link, the oscillatory axis of said housing when extended substantially intersecting the longitudinal axis of said feeding-foot stem at a point between the ends of said guiding means and distanced from said ends, and said link moving in lines substantially parallel to said 105 longitudinal axis.

3. In a folding machine, an oscillatory feeding-foot housing, a feeding-foot, guiding means between said housing and feeding-foot, and a rocker-arm and link having 115 connection with said feeding-foot for reciprocating the same lengthwise of said guiding means, the connections between said rocker-arm and feeding-foot embracing a spaced connection for causing idle movement of said rocker-arm with relation to said feeding-foot during portions of the oscillatory movements of said feeding-foot, and resilient means for retracting said feeding-foot with relation to said housing.

4. In a folding machine, an oscillatory feeding-foot housing comprising a guideway, a feeding-foot comprising a stem guided by said guideway, a rocker-arm, and a link having operative connections with 120 125 130

said arm and said feeding-foot stem for reciprocating said feeding-foot, the axis of oscillation of said feeding-foot housing and the axes of said operative connections, when 5 said axes are extended, substantially intersecting the longitudinal axis of said feeding-foot stem, and said axis of oscillation of said feeding-foot housing, when extended, being between and distanced substantially 10 from both ends of said feeding-foot stem.

5. In a folding machine, the combination of a housing having a recess therein provided with an upwardly opening mouth, a rock-shaft therefor secured thereto at one 15 side of said recess, a feeding-foot having longitudinal reciprocation lengthwise of and guided by said housing at the other side of said recess, and means for reciprocating said feeding-foot received in said recess and extending upwardly through said upwardly 20 opening mouth.

6. In a folding machine, the combination of a housing having a guide, a feeding-foot guided by said guide, means for oscillating 25 said housing, an arm and link having spaced connection with said feeding-foot for moving idle with relation to said feeding-foot during portions of their movements and for longitudinally reciprocating said feeding- 30 foot during other portions of their movements, and resilient means for normally depressing said foot with relation to said housing.

7. In a folding machine, the combination 35 of a housing having a guide, a feeding-foot guided by said guide, a presser-foot, a rock-shaft for oscillating said housing, and a rock-shaft having opposed connections with said feeding-foot and presser-foot for reciprocating the same respectively during 40 opposite movements of said second-named rock-shaft.

8. In a folding machine, the combination 45 of a housing provided with a guide, a feeding-foot guided by said guide, a presser-foot, a rock-shaft for oscillating said housing, and a rock-shaft having opposed and spaced connections with said feeding-foot and presser-foot for reciprocating the same 50 respectively during opposite movements of said second-named rock-shaft.

9. In a folding machine, the combination 55 of a housing provided with a guide, a feeding-foot guided by said guide, a presser-foot, a rock-shaft for oscillating said housing, and a rock-shaft having opposed and spaced connections with said feeding-foot and presser-foot for reciprocating the same alternately during opposite movements of 60 said second-named rock-shaft, the spaces of said spaced connections permitting timed alternate operations of said feet by said second-named rock-shaft.

10. In a folding machine, the combination 65 of a presser-foot, a rocker-part, and a coiled

compression spring between said presser-foot and rocker-part whose compression is slight in extent and which becomes longitudinally rigid when said compression has taken place for moving said presser-foot 70 through the medium of said compression spring when longitudinally rigid.

11. In a folding machine, the combination of a presser-foot, a rock-shaft having a contact-part thereon for reciprocating the same, 75 and a coiled compression spring between said presser-foot and rock-shaft whose compression is slight in extent and which becomes longitudinally rigid when said compression has taken place, said spring being 80 shorter than the longest distance of separation in line therewith between said contact-part and presser-foot for providing a space between said spring and one of said last-named parts during part of the rocking 85 movement of said contact-part.

12. In a folding machine, the combination of a presser-foot, an operating part for reciprocating the same, and a coiled compression spring between said presser-foot and 90 last-named part whose compression is slight in extent and which becomes longitudinally rigid when said compression has taken place and acts as a cushion-impact and moving device for raising said presser-foot. 95

13. In a folding machine, the combination of a feeding-housing, means for rocking said housing, a feeding-foot guided by and moving with said housing, a presser-foot lever, and a rocker-part between said feeding-foot 100 and presser-foot lever having operating parts thereon for said feeding-foot and presser-foot lever for moving said feeding-foot and presser-foot lever respectively during opposite movements of said rock-shaft. 105

14. In a folding machine, a feeding-foot, and means for oscillating said feeding-foot for causing feeding movement thereof, said means comprising links, rocker-arms pivoted to one of the ends of said links, one of 110 said arms being a rocker-arm for operating said links, the other of the ends of said links having articulation with each other, said links simultaneously constituting a compression member and a tension member in 115 effecting each oscillating movement of said feeding-foot, and means for changing the positions of said last-named articulation with relation to the axes of oscillation of said rocker-arms for changing the extent of 120 said oscillation of said feeding-foot.

15. In a folding machine of the class described, the combination of feeding means for the material operated on, a stationary folder, a fold-presser, a reciprocating knife 125 for the material operated on, means for reciprocating said knife, treadle actuated means for controlling the position of said knife with relation to said material during the operation of the machine, and means for 130

- shifting said stationary folder into inactive position.
16. In a folding machine, the combination of a feeder, and means for causing feeding movement of said feeder comprising a pair of rockable arms, one of said rockable arms having operative connection with said feeder for moving the same and the other of said rockable arms being an operating arm, and links articulated respectively to said arms and articulated to each other, said last-named articulation being normally substantially coincident with the rocking axis extended of said operating rockable arm and shiftable with relation to said first-named articulations. 70
17. In a folding machine, the combination of a feeder, and means for causing feeding movement of said feeder comprising a pair of rockable arms, one of said rockable arms having operative connection with said feeder for moving the same, an eccentric for operating the other of said arms, and links articulated respectively to said arms and articulated to each other, the axis of said last-named articulation being normally substantially coincident with the rocking axis extended of said rockable arm operated by said eccentric. 75
18. In a folding machine, the combination of a feeder, and means for causing feeding movement of said feeder comprising a pair of rockable arms whose rocking axes are in offset relation, one of said rockable arms having operative connection with said feeder for moving the same, the other of said arms being an operating arm, and links articulated respectively to said arms and articulated to each other, said links simultaneously constituting a compression member and a tension member, said last-named articulation being shiftable toward and from the rocking axis, when extended, of said operating rockable arm. 80
19. In a folding machine, the combination of a feeder, and means for causing feeding movement of said feeder comprising a plurality of rocker-arms, one of said rocker-arms having operative connection with said feeder for moving the same, the other of said rocker-arms being an operating arm, links articulated respectively to said arms and articulated to each other, and shifting means for said last-named articulation for changing the lengths of feeding movement of said feeder, said operating arm and said links being substantially parallel adjacent one of the limits of movement of said shifting means. 85
20. In a folding machine, the combination of a feeder, and means for causing movement of said feeder comprising a plurality of rock-shafts, arms thereon, links articulated respectively to said arms and articulated to each other, one of said arms being an operating arm for said links, said links simultaneously constituting a compression member and a tension member at each of said movements of said feeder, and adjustable shifting means for said last-named articulation. 90
21. In a folding machine, the combination of a feeder, means for causing feeding movement of said feeder comprising a plurality of rocker-arms, one of said rocker-arms having operative connection with said feeder for moving the same, the other of said rocker-arms being an operating arm, links articulated respectively to said arms and articulated to each other, said links simultaneously constituting a compression member and a tension member at each of the feeding movements of said feeder, shifting means for said last-named articulation, and a stop for said shifting means. 95
22. In a folding machine, the combination of a feeder, means for causing feeding movement of said feeder comprising a plurality of rocker-arms, one of said rocker-arms having operative connection with said feeder for moving the same, and the other of said rocker-arms being an operating arm, links articulated respectively to said arms and articulated to each other, shifting means for said last-named articulation, and means for adjusting the range of movement of said shifting means, said operating arm and links being substantially parallel with each other adjacent one of the limits of said range of movement of said shifting means. 100
23. In a folding machine, the combination of a feeder, means for causing feeding movement of said feeder comprising a plurality of rocker-arms, one of said rocker-arms having operative connection with said feeder for moving the same, and the other of said rocker-arms being an operating arm, links articulated respectively to said arms and articulated to each other, said links being simultaneously respectively a compression member and a tension member at each feeding movement of said feeder, shifting means for said last-named articulation, and a pair of stops for said shifting means having adjustment between them. 105
24. In a folding machine, the combination of a plurality of rock-shafts in offset relation, a feeder having operative connection with one of said rock-shafts, the other of said rock-shafts being an operating rock-shaft, arms on said rock-shafts, links articulated respectively to said arms and articulated to each other, said links being simultaneously respectively a compression member and a tension member, and means for shifting said last-named articulation toward and from the rocking axis extended of said operating rock-shaft for adjusting the feeding movement of said feeder. 110
25. In a folding machine the combination of a plurality of rock-shafts in offset rela- 115

- tion, a feeder having operative connection with one of said rock-shafts, an eccentric drive for the other of said rock-shafts, arms on said rock-shafts, links articulated respectively to said arms and articulated with each other, said links being simultaneously respectively a compression member and a tension member, means for shifting said last-named articulation toward and from the articulation with that rock-shaft having said eccentric drive connection therewith for adjusting the feeding movement of said feeder, and adjusting means for said last-named means.
- 15 26. In a folding machine, the combination of a rock-shaft, a feeder having operative connection therewith, a folder, a second rock-shaft offset with relation to said first-named rock-shaft, arms on said rock-shafts, links articulated at one of their ends to said arms and articulated at their other ends to each other and arranged for oscillating said feeder with predetermined forward limits of movement with relation to said folder, and means for shifting said last-named articulation toward and from the axial line of said second-named rock-shaft whereby the feeding movement of said feeder is adjusted in extent from its point of said forward limit of movement.
- 30 27. In a folding machine, the combination of a feeding-foot, a presser-foot, a rock-shaft having operative connection with said feeding-foot for rocking the same, a rock-shaft having operative connection with said presser-foot and feeding-foot for reciprocating the same, a third rock-shaft in offset relation to said first-named rock-shaft, arms on said first-named and third-named rock-shafts, links between said arms having articulation with each other and the said arms, and eccentric drives for said first-named and third-named rock-shafts.
- 35 28. In a folding machine, the combination of folding instrumentalities arranged to fold the edge of flexible material, a feeding-device for said material, and means for causing intermittent feeding movements of said feeding-device, said means comprising an operating part, an operated part having connection with said feeding-device, constituting a pair of parts, and a pair of links articulated together at one of their ends and at the other of their ends having operative connection with said pair of parts, said links simultaneously constituting a compression-member and a tension-member during each feeding movement of said feeding-device.
- 40 29. In a folding machine, the combination of folding instrumentalities arranged to fold the edge of flexible material, a feeding-device for said material, means for causing intermittent feeding movements of said feeding-device, said means comprising an operating part, an operated part having connection with said feeding-device, constituting a pair of parts, and a pair of links articulated together at one of their ends and at the other of their ends having operative connection with said pair of parts, said links simultaneously constituting a compression-member and a tension-member during each feeding movement of said feeding-device.
- 45 30. In a folding machine, the combination of folding instrumentalities arranged to fold the edge of flexible material, a feeding-device for said material, means for causing intermittent feeding movements of said feeding-device, said means comprising an operating part, an operated part having connection with said feeding-device, constituting a pair of parts, and a pair of links articulated together at one of their ends and at the other of their ends having operative connection with said pair of parts, said links simultaneously constituting a compression-member and a tension-member during each feeding movement of said feeding-device.
- 50 31. In a folding machine, the combination of folding instrumentalities arranged to fold the edge of flexible material, a feeding-device for said material, means for causing intermittent feeding movements of said feeding-device, said means comprising an operating part, an operated part having connection with said feeding-device, constituting a pair of parts, and a pair of links articulated together at one of their ends and at the other of their ends having operative connection with said pair of parts, said links simultaneously constituting a compression-member and a tension-member during each feeding movement of said feeding-device.
- 55 32. In a folding machine, the combination of a goose-neck frame having an overhanging bracket provided with an overhanging outer end, a bearing on said outer end, a feeding-head, a rock-shaft for said head journaled in said bearing, a fold-presser, an operating shaft therefor, and operative con-

necting means between the latter and said fold-presser located entirely under said head and bearing.

33. In a folding machine, the combination 5 of a folder, a fold-presser in rear thereof, a knife-support, provided with a rearward extension above said folder, and a knife secured to the latter and operating in front of said folder and closely adjacent thereto, 10 said fold-presser, extension and knife forming a channel in which said folder is located.

34. In a folding machine, the combination 15 of a material support, and a knife having a lateral cutting edge and a bottom cutting edge at acute angles with relation to each other, said knife being movable toward the feeding line of the material at an angle to said support.

35. In a folding machine, the combination 20 of a material support, a knife-support pivoted below said material support in a vertical plane to the side of the vertical plane of the line of feed, and a knife having an inclined cutting edge at that side thereof 25 adjacent to said line of feed and an inclined lower cutting edge, said cutting edges being at acute angles to each other for presenting a cutting corner to the material.

36. In a folding machine, the combination 30 of folding instrumentalities arranged to fold the edge of flexible material, a feeding-device for said material, means for causing intermittent feeding movements of said feeding-device, said means comprising an 35 operating part, an operated part having connection with said feeding-device, constituting a pair of parts, and a pair of links articulated together at one of their ends and at the other of their ends having operative 40 connection with said pair of parts, said links simultaneously constituting a compression-member and a tension-member during each of said intermittent feeding movements of said feeding-device, means under the control 45 of the operator during the operation of the machine for moving the articulating axis between said links with relation to said operating part for controlling the lengths of steps of feed of said feeding-device, said 50 last-named means comprising a movable feed-controlling member, yielding means tending normally to move said movable feed-controlling member to one limit of its path, and an adjustable stop for adjustably 55 limiting the extent of movement of said movable feed-controlling member.

37. In a folding machine, the combination 60 of folding instrumentalities arranged to fold the edge of flexible material, a feeding-foot for said material, and means for oscillating said feeding-foot for causing feeding and retracting movements thereof, said means comprising links, rocker-arms pivoted to one of the ends of said links, one of said rocker-arms arranged for operating said links, the

other of the ends of said links having articulation with each other, and means for changing the positions of said last-named articulation with relation to the pivotal axis extended of one of said rocker-arms for changing the extent of said oscillation of said feeding-foot, said links being respectively a tension-member and a compression-member at each movement of said links for moving said feeding-foot in one direction. 70

38. In a folding machine, the combination with a fold-presser and a knife, of a stationary folder between said knife and fold-presser, and means for shifting said stationary folder into inactive position. 80

39. In a folding machine, the combination of a pivoted fold-presser housing, a pivoted fold-presser, and a pivoted knife-lever having coincident pivotal axes. 85

40. In a folding machine, the combination of a pivoted fold-presser and a knife-lever having coincident pivotal axes, operating means therefor comprising a rocker-part having eccentric connection with said knife-lever, a knife on said knife-lever, and means 90 for swinging said rocker-part whereby said knife is rendered inactive.

41. In a folding machine, the combination of folding instrumentalities arranged to fold the edge of flexible material, a feeding-foot for feeding said material and means for oscillating said feeding-foot, said means comprising a pair of links, a rocker-arm having pivotal connection with one of the ends of one of said links, the corresponding end of the other of said links having pivotal connection with said feeding-foot, the other of the ends of said links having articulation with each other, the pivotal axes of said pivotal connections lying on 100 the arc of a circle having the axis of said articulation as its center, and means for adjusting said axis of articulation toward and from the rocking axis of said rocker-arm. 105

42. In a folding machine, the combination of folding instrumentalities arranged to fold the edge of flexible material, a feeder for feeding said material, and means for causing intermittent feeding movements of said feeder comprising a pair of rockable 110 arms, one of said rockable arms having operative connection with said feeder for moving the same and the other of said rockable arms being an operating arm, links articulated respectively to said arms and articulated to each other, and means for shifting said last-named articulation into and out of substantial coincidence with the rocking axis extended of said operating rockable arm. 115

43. In a folding machine, the combination of folding instrumentalities arranged to fold the edge of flexible material, a feeder for feeding said material, and means for causing intermittent feeding movements of said feeder comprising a pair of rockable 120 arms

5 arms, one of said rockable arms having operative connection with said feeder for moving the same and the other of said rockable arms being an operating arm, links
 10 articulated respectively to said arms and articulated to each other, and means under manual control of the operator during the operation of the machine for shifting said last-named articulation into and out of sub-
 15 stantial coincidence with the rocking axis extended of said operating rockable arm.

44. In a folding machine, the combination of folding instrumentalities arranged to fold the edge of flexible material, a feeder
 15 for feeding said material, and means for causing intermittent feeding movements of said feeder comprising a pair of rockable arms, one of said rockable arms having operative connection with said feeder for moving the same and the other of said rockable arms being an operating arm, and links
 20 articulated respectively to said arms and to each other, said links being respectively a compression-member and a tension-member
 25 during each movement of said feeder effected through said links.

45. In a folding machine, the combination of folding instrumentalities arranged to fold the edge of flexible material, a feeder
 30 for feeding said material, and means for causing intermittent feeding movements of said feeder comprising a pair of rockable arms, one of said rockable arms having operative connection with said feeder for moving the same and the other of said rockable arms being an operating arm, and links
 35 articulated respectively to said arms and to each other, said links being respectively a compression-member and a tension-member
 40 during each movement of said feeder effected through said links, and means for adjusting said articulation articulating said links to each other toward and from the rocking axis of said operating rockable arm.

45. 46. In a folding machine, the combination of folding instrumentalities arranged to fold the edge of flexible material, a feeder
 50 for feeding said material, and means for causing intermittent feeding movements of said feeder comprising a pair of links, a part having operative connection with said feeder, an operating arm, said links articulated respectively to said part and arm and articulated to each other, said last-named
 55 arm and said links being normally located side by side, and shifting means for shifting said links into and out of substantial parallelism with said last-named arm, said links being respectively a compression-member and a tension-member during each movement of said feeder effected through said links.

47. In a folding machine, the combination of folding instrumentalities arranged to fold
 60 the edge of flexible material, a feeder for

feeding said material, and means for causing intermittent feeding movements of said feeder comprising a pair of links, a part having operative connection with said feeder, an operating arm, said links articulated respectively to said part and arm and articulated to each other, said last-named arm and said links being normally located side-by-side, said links being respectively a compression-member and a tension-member
 70 during each movement of said feeder effected through said links, shifting means for shifting said links into and out of substantial parallelism with said last-named arm, and means for adjusting the range of
 75 movement of said shifting means.

48. In a folding machine, the combination of folding instrumentalities arranged to fold the edge of flexible material, a feeder for
 80 feeding said material, means for causing intermittent feeding movements of said feeder comprising an operating arm, a pair of substantially parallel links located side by side, said links at one of the ends thereof being articulated respectively to said feeder for moving the same and to said operating arm, said links at the other of their ends being articulated to each other, said links being respectively a compression-member and a tension-member at each movement of said
 85 feeder effected through said links, and shifting means for said last-named articulation for shifting said links into and out of substantial parallelism with said operating arm.

49. A folding machine having, in combination, a frame with an outwardly projecting arm provided with a stationary work supporting portion, a folder for turning over the edge to be folded and means for pressing down the edge to be folded, both said folder and said pressing means being mounted on the end of said arm, and means within said arm for actuating said pressing means.

50. A folding machine having in combination, a frame having an outwardly projecting arm provided with a stationary work supporting portion of small cross section, a folder, fold pressing means and snipping means all mounted on said arm adjacent to the end thereof and means located in said arm for actuating said fold pressing and said snipping means.

51. A folding machine having, in combination, a frame with an outwardly projecting arm provided with a stationary work supporting portions, means for turning over and means for pressing down the edge to be folded, both of said means being mounted on the end of the arm and means located within said arm for actuating said pressing means.

52. A folding machine having, in combination, a frame with an outwardly projecting arm above its base, there being a free

- and unobstructed space on all sides of said arm, a stationary work support mounted on the end of said arm, means for turning over the edge of material to be folded, means for 5 pressing down the turned over edge, said turning means and said pressing means being carried by said arm, and means within the arm for actuating said fold pressing means.
- 10 53. A folding machine, having, in combination, a frame carrying an outwardly extending arm at a point above its base, a folder and fold pressing means mounted upon the arm, and actuating mechanism for 15 said fold pressing means within said arm.
54. A folding machine, having, in combination, a frame with an outwardly projecting arm above its base, there being a free and unobstructed space on all sides of said arm, 20 folding means, fold pressing means and snipping means all mounted upon said arm and means for operating said fold pressing and said snipping means.
55. A folding machine having, in combination, a frame provided with an outwardly projecting arm, a driving shaft located in the base of the frame, folding instrumentalities including a folder, a presser and a knife mounted upon said arm, actuating members 25 connected respectively with said presser and knife, said members located in said arm and extending lengthwise thereof, and means for operating said members from said driving shaft.
56. A folding machine having, in combination, a frame provided with an outwardly projecting arm, a driving shaft located in the base of the frame, folding instrumentalities including a fold-pressing member and 30 a knife mounted upon said arm, actuating members connected respectively with said fold-pressing member and knife, said actuating members located in said arm, and means for operating said actuating members from 35 said driving shaft.
57. A folding machine, having, in combination, a frame provided with an outwardly
- projecting arm and a goose neck arm above said outwardly projecting arm having a bearing head at its outer end located above 50 the outer end of said first named arm, a driving shaft located in the base of the frame, feeding means mounted on said head, an actuating member on said head therefor, folding instrumentalities including a folder, a 55 fold presser and a knife mounted on said outer end of said first named arm, actuating members connected respectively with said fold presser and said knife located on said outer end of said first named arm and means 60 for operating said several actuating members from said driving shaft.
58. In a folding machine, the combination of means for turning over and means for pressing down the edge to be folded with 65 means for feeding the material to be folded intermittently into position to have its margin operated upon; said feeding means including a feeding member, a rock-shaft for oscillating said feeding member to feed the 70 material and means controlled by the operator for varying the length of the arc of rocking movement of said rock-shaft during the operation of the machine.
59. In a folding machine, the combination 75 with means for turning and means for pressing down the edge to be folded of means for feeding the material; said feeding means comprising an idler roll, a feeding member coöoperating with said roll, a rock-shaft for 80 oscillating said feeding member to feed the material, means for rocking said shaft and means whereby the length of the arc of the rocking movement of said shaft may be controlled by the operator during the operation 85 of the machine to vary the length of the feeding movement of said feeding member.

In testimony whereof, I have signed my name hereto in the presence of two subscribing witnesses.

WILLIAM F. LAUTENSCHLAGER.
